CENTRIFUGAL PUMP.

1,074,794.

Specification of Letters Patent.

Patented Oct. 7, 1913.

Application filed March 26, 1910. Serial No. 551,676

To all whom it may concern:

Be it known that I, BEN HUNT, a citizen of the United States, and a resident of Fresno, in the county of Fresno and State of California, have invented new and useful improvements in Centrifugal Pumps, of which the following is a specification.

The invention relates to improvements in that class of pumping apparatus known as centrifugal pumps and has particular reference to improvements in the design of the runner or impeller whereby several of the power losses now present are eliminated.

The action of the impeller during the operation of the pump is to hurl the water into the volute chamber from the impeller chamber, thereby causing a drop in pressure or a partial vacuum in the impeller-chamber. The effect of this drop in pressure is to cause the water to rise in the suction tube and flow into the casing, and as the action of the impeller is continuous, a partial vacuum exists in the impeller-chamber. The effect of the partial vacuum is to exert a pulling force on the sides of the casing.

In open runner pumps the impeller blades project from the face of the runner adjacent to the suction inlet. The other or rear face of the runner lies in close relation to the back wall of the casing. The water entering the casing is therefore immediately engaged by the impeller vanes and its progress is not interfered with by the body portion of the runner.

The object of the present invention is to increase the efficiency of a centrifugal pump, by eliminating the energy losses caused by the longitudinal pull on the impeller.

A further object of the invention is to balance the longitudinal forces acting on the impeller in the casing, without increasing the friction of the liquid in the casing or retarding its flow.

To these and other objects the invention consists of an impeller for centrifugal pumps so designed and constructed that a force is exerted in the impeller equal and opposite to the forces on the impeller due to the various pressures within the casing.

The following description explains at length the nature of my said improvements

and the manner in which I proceed to construct and apply the same in the production of a centrifugal pump, reference being had to the drawings accompanying this specification.

Figure 1 is a side elevation of a centrifugal pump, part of the casing being broken away to show the impeller. Fig. 2 is a side-view of the impeller removed from the pump showing one means of producing the counter-balancing force. Fig. 3 is a front or face view of the impeller shown in Fig. 2. Figs. 4, 5, 6, 7, 8 and 9 show modifications of the means for producing the counter-balancing force. Fig. 4 being a side-view of the impeller; Fig. 5 a face-view showing the balancing vane mounted between the impeller vanes; Fig. 6 a cross section through the line *a—a*—Fig. 5. Fig. 7 is a cross-sectional detail of another modification taken on a line such as *a—a*—Fig. 5. Fig. 8 shows a pump provided with an impeller curved in a plane at right angles to the plane of rotation to allow the water to travel therethrough on a smooth curve and also to produce the counter-balancing forces, and Fig. 9 is a side-view of an impeller having the impeller blades formed in a spiral involute curve; the blades being set at an acute angle to the web.

The essential features of my invention consist of a vane, blade or curvature so fixed or located on or in the impeller so as to lie at an angle with the plane of rotation thereof; or the path of the water and adapted by its position to come in contact with the water with the effect of producing a force in the opposite direction to the forces caused by the suction or pressure. These vanes or blades are preferably arranged on the impeller vanes, or in the body of the impeller and lie angularly to the plane of rotation of the impeller progressing along the face of the impeller and digressing from the rear wall or web in the path of rotation of the impeller. The vanes are also arranged to lie within the circle described by the outer points of the impeller and therefore do not extend into the volute chamber, and interfere with the flow of water therein. The angular displacement of the vanes, which I

will term counter-balancing vanes, is varied according to the speed or lift for which the pump is designed.

The invention does not apply to the main body of the pump, the base 1 and the casing 2 remaining the same as in general use. The impeller shaft 5 is supported in the usual way by the outboard bearing 4 and the water enters the casing through the usual 10 section elbow 3.

The impeller is preferably formed of a casting comprising the hub 6, the impeller vanes 8 and the web plate 7 rigidly connecting the vanes and the hub at the back or 15 rear side of the impeller. The vanes 8 may be of any desired shape or curvature depending upon the amount of water to be raised or the speed at which the impeller is run. The vanes project from the front 20 face of the web plate 7 into the working chamber of the pump, the web plate lying adjacent to the back wall out of the path of the water. To preserve continuity of the water in the working chamber, the walls 25 thereof converge toward the circumference and the impeller is formed with the same angle of convergence.

In one form of construction the blade or vane 9 for producing the counter-balancing 30 force is arranged on the face of the impeller vanes 8, running diagonally across the face and extending from the front face at the extremity to the rear face at a point 12 approximately midway of the length of the 35 vane. The action of the water on the angularly disposed vane produces a component force parallel to the axis of the runner.

The impeller, as shown in Fig. 3 revolves in a clockwise direction, therefore, the vanes 40 9 acting on the water set up a strain tending to force the impeller backward toward the rear wall of the casing. The length and curvature of these vanes may be arranged as desired depending on the force to be overcome.

In Fig. 4 I have shown a modification in which I employ a groove or slot 10 in place of the upstanding vane 9. The effect in either case is the same. The water in the 50 casing is impelled by the outer face 15 of the impeller vanes 8, consequently the slot 10 will act with equal efficiency as the vane.

Another modification is shown in Figs. 5 and 6 wherein the counter-balancing force 55 is generated by the action of the water on the blade 16 arranged between two succeeding impeller vanes 8. The blade 16 is placed approximately at right angles to the direction of flow of the water and in its other dimension angularly to the path of the water, to cause a pressure parallel to the axis of the impeller. A single blade 16 may be used or several blades may be similarly placed between the other impeller vanes. Another 60 method of causing the counterbalancing ef-

fect is shown in Fig. 7, wherein the edge 11 of the web 7 lying in an approximately radial direction between two impeller vanes is curved to produce the required component force.

In Fig. 8 I have shown a modification wherein the desired effect is obtained by curving the web 7 in a plane at right angles to the plane of rotation of the impeller, and curving the rear wall of the pump body to conform thereto. The water moving radially over the web encounters the concave face 18 and is turned outwardly causing a corresponding pressure to be exerted parallel to the axis of rotation. By varying the radius of curvature of the concave face the longitudinal pressure caused by the moving water is varied. The requirements of the pump being known, the curvature of the web is formed to generate the necessary force. The water entering the pump casing travels on a smooth curve therethrough thereby eliminating the losses due to the sudden change of velocity in pumps as now constructed.

Fig. 9 shows a modification in which the impeller blades are set at an acute angle to the web, causing the resultant velocity of the water to lie in a path at an acute angle to the axis of the impeller. The horizontal component of this resultant velocity produces a force parallel to the axis of the impeller in the opposite direction to the forces caused by the suction.

Throughout the specification and drawings, I have described an impeller of the open-runner type, but it is evident that the same improvement can be applied to an impeller of the closed runner type, to produce the same effects. It is understood, therefore, that I do not limit myself to the exact construction shown as a means of accomplishing the counter-balancing effect, as these and many other modifications may be arranged without varying from the spirit of my invention.

I claim:—

1. In a centrifugal pump, a runner provided with vanes on the outer faces of the impeller blades, arranged angularly to the plane of rotation of the impeller.

2. In a centrifugal pump, a runner provided with means adapted to engage the water in the volute chamber, said means being arranged angularly to the path of the water in said chamber and adapted to produce a thrust in the opposite direction to the suction thrust.

3. In a centrifugal pump, a casing having a suction inlet at one side, a runner in said casing, and vanes on the outer faces of said runner adapted to produce a thrust on the runner in opposition to the suction pull on the runner.

4. In a horizontal shaft centrifugal pump,

a casing having a suction inlet at one side, a runner rotatably mounted in said casing, and vanes on the outer faces of said runner arranged at an angle to the plane of rotation thereof, said vanes being arranged so that their rear ends lie closer to the suction side of the pump than their leading ends.

5. In a centrifugal pump, a runner having curved impeller blades extending outward to a circumscribing circle, and vanes on the impeller blades within said circle, arranged at an angle to the plane of rotation of the runner.

6. In a centrifugal pump, a runner provided with a plurality of impeller blades which digress outwardly at an angle to the radius, and vanes arranged on said blades at an angle to the plane of rotation of the runner.

7. In a centrifugal pump, a runner provided with a plurality of impeller blades

which progressively decrease in width toward the periphery of the runner, and vanes on said blades angularly disposed to the plane of rotation.

25

8. In a centrifugal pump, a runner having impeller blades, and means on the outer faces of said blades and arranged angularly to the path of the water through the pump for producing a thrust in the opposite direction to the suction thrust.

30

9. In a centrifugal pump, a casing having a suction inlet and a discharge, a runner in said casing having impeller blades disposed angularly to the radius, and vanes on said blades arranged to exert a counter-balancing pressure to the force due to the suction thrust.
